Primary Examiner — Cynthia R Underwood*(74) Attorney, Agent, or Firm* — St Onge Steward
Johnston & Reens LLC(57) **CLAIM**

The ornamental design for a cord handler, as shown and described.

DESCRIPTION

FIG. 1 is a top, front and left side perspective view of a first embodiment of a cord handler in accordance with the new design showing the cord handler in a closed position;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and

FIG. 7 is a right side elevation view thereof;

FIG. 8 is a top, front and left side perspective view thereof showing the cord handler in an open position;

FIG. 9 is a top plan view thereof;

FIG. 10 is a bottom plan view thereof;

FIG. 11 is a front elevation view thereof;

FIG. 12 is a rear elevation view thereof;

FIG. 13 is a left side elevation view thereof; and,

FIG. 14 is a right side elevation view thereof.
